UNITED STATES PATENT OFFICE.

ALEXANDER FERDINAND VICTOR, OF TOLEDO, OHIO.

PICTURE-DISPLAYING MACHINE.

1,019,932.

Specification of Letters Patent. Patented Mar. 12, 1912.

Application filed February 23, 1910. Serial No. 545,427.

To all whom it may concern:

Be it known that I, ALEXANDER FERDINAND VICTOR, a subject of the King of Sweden, residing at Toledo, in the county of Lucas and State of Ohio, have invented new and useful Improvements in Picture-Displaying Machines, of which the following is a full, clear, and exact description.

My invention relates to a picture displaying machine of the old zoetrope order in which the eye of the operator is focused on one place past which a series of pictures showing living objects in different positions, move rapidly, and are thereby given the appearance of being animated.

The object of my invention however, is to provide a simple and comparatively inexpensive apparatus particularly adapted to use a rotary transparent film having a curved series of pictures arranged thereon, for which I applied for Letters Patent of the United States, January 28, 1910, Serial No. 540,541, and to provide for the easy and convenient displacing and removal of one film and the substitution of another. This I accomplish by the means hereinafter fully described and as particularly pointed out in the claims.

In the drawings:—Figure 1 is a perspective view of my invention. Fig. 2 is a vertical longitudinal section therethrough. Fig. 3 is a vertical transverse section. Fig. 4 is a fragmentary view showing the revolving plate actuating mechanism.

In the drawings A represents a suitable pedestal, the upper end of which is divided to adapt it to receive the pivotal knuckle a, of a plate a' secured to the center of the underside of a rectangular box B. The top of the box serves as a bed or platen which is, preferably, near one longitudinal side provided with a rectangular or other suitably shaped opening, d. Below this opening the box is provided with an artificial light source J, which in the drawings is shown to be electric. Hinged to the upper edge of the side of this box near which opening d is located, and arranged in the same transverse plane thereon, is an arm or bracket C, that is bifurcated commencing at a point near its hinged end, and extending toward and to the opposite end thereof.

D represents a transparent circular film of celluloid or other suitable material, for which, as stated, I have already applied for Letters Patent, and which, preferably has

a radius slightly exceeding the length of the slot of the bifurcated arm C. The circumferential edges of this plate are reinforced by a suitable binding, or by folding its edges back upon itself, or in any other suitable manner, and it is provided with a spirally arranged series of equi-distant perforations, k, therein, commencing at the outer edge of the disk and terminating near the axis thereof, and extending parallel to a spiral series of pictures on said film.

In order to display the pictures thereon consecutively, this film is rotated and at the same time drawn sidewise, in order that said pictures can be brought in position over opening d of box B one after the other in proper order. This is accomplished by means of a reciprocal pick e, which is adjustable in the end of a reciprocal bar or pitman-beam E, one end of which is slotted and engages a stationary pin f projecting from the adjacent inner side of the box, and the other end of which is given a movement like a pitman by means of wheel F, that has a wrist-pin g extending through a suitable opening in the end of said pitman-beam, near the pick. Wheel F is suitably mounted upon a shaft G, which latter extends under the top of the box in a transverse plane parallel to that of the bifurcated arm or bracket C to the opposite side of the box, where it is provided with suitable bearings. Near these last mentioned bearings, shaft G has a pinion mounted thereon, that is engaged by a comparatively large gear h, which latter is secured on the inner end of a spindle R, extending through bearings in the side of the box and has a handle H on its outer end for revolving it.

When the film is rotated by means hereinbefore described to bring the spirally arranged series of pictures thereon in regular succession over opening d, the operator's gaze can be focused on the picture on the film over opening d by means of microscopic or sight-tube I. This tube I is mounted on the end of a plate K, whose opposite end is provided with suitable knuckles and hinged to a plate k' secured to the side of the box opposite bracket C. Near its hinged end this plate K is provided with downturned lugs or feet m, which, when the said plate is moved so as to bring the sight-tube in axial alinement with opening d will bear upon the top of the box and support said tube above the platen so that the film can

- move between the two. When my improved machine is not in operation, plate K is lifted and bracket C swung over the top of the box, and then said plate is again lowered 5 into the position shown in the drawings. When it is desired to use the machine, the said plate is lifted, and bracket C again moved into the horizontal position shown in the drawings, until it rests upon a strut 10 n secured to and projecting from the supporting-plate of said arm, and a suitable centering pin o is inserted in the central opening of the film and the plate is moved so that the barrel of the pin will enter be- 15 tween the bifurcations of bracket C, and until the first picture of the spiral series thereon is over the opening d in the top of the box. When in this position the lamp J is turned on, and the film adjusted so that 20 the pick e will enter the proper perforation, therein, and then the pick is rotated by the means hereinbefore explained to engage said perforations b and rotate film as stated. As the pick revolves in a plane tangential 25 to the center of the film, every time it reciprocatcs, it will draw the film laterally to a slight extent sufficient to bring the spirally arranged series of pictures consecutively in position to be seen through the sight-tube.
- 30 What I claim as new is:—
1. A picture displaying machine comprising a suitable platen having an opening therein, a superimposed sight-tube, a rotatable film between said tube and platen, de- 35 vices for rotating and moving said film laterally, and means projecting beyond said platen for centering said film and guiding the lateral movement thereof.
  2. A picture displaying machine comprising a suitable platen having an opening therein, a superimposed sight-tube, means projecting beyond said platen for centering and guiding the lateral movement of the axis of a rotatable film, between said tube and 40 opening and common devices that impart both an intermittent rotary movement to said film and simultaneously move said film laterally.
  3. A picture displaying machine comprising a suitable platen having an opening therein, a superimposed sight-tube, a rotatable film between said tube and platen, de- 45 vices for rotating and moving said film laterally, and a bracket for centering said film and guiding the lateral movement thereof.
  4. A picture displaying machine comprising a suitable platen having an opening therein, a superimposed sight-tube, a rotatable film between said tube and platen, de- 50 vices for intermittently rotating and moving said film laterally, and means for centering said film and guiding the lateral movement thereof.
  - 65 5. A picture displaying machine comprising

70 ing a suitable platen having an opening therein, a superimposed sight tube alining with said opening, a hinged bracket adapted to support and guide the lateral movement of the centering element of a rotatable picture film, and devices for rotating and moving the film laterally.

75 6. A picture displaying machine comprising a suitable platen having an opening therein, a superimposed sight-tube alining with said opening, a hinged slotted bracket adapted to support and guide the lateral movement of the centering element of a rotatable picture film, and devices for rotating and moving the film laterally.

80 7. A picture displaying machine comprising a suitable platen having an opening therein, a superimposed sight-tube supporting-plate, upon which said sight-tube is mounted, means projecting beyond said platen for centering and guiding the lateral movement of the axis of a rotatable film between said tube and platen, and devices for rotating and moving the film laterally.

85 8. A picture displaying machine comprising a suitable platen having an opening therein, a superimposed sight-tube, a hinged supporting-plate upon which said tube is mounted, means for centering and guiding the lateral movement of the axis of a rotatable film between said tube and platen, and devices for 90 rotating and moving the film laterally.

9. A picture displaying machine comprising a suitable platen having an opening therein, a superimposed sight-tube alining with said opening, a supporting-plate hinged at one side of said platen upon which said tube is mounted, a bracket hinged to and adapted to project from the opposite side of said platen, and adapted to support and 100 guide the lateral movement of the centering element of a rotatable transparent picture film, and devices for rotating and moving the film laterally.

10. A picture displaying machine comprising a suitable platen having an opening therein, a superimposed sight-tube alining with said opening, a bracket adapted to center and guide the lateral movement of the centering element of a rotatable picture film, actuating devices for imparting an intermittent rotary movement and a lateral movement to said film consisting of a reciprocal pitman beam, and a pick in the end thereof adapted to engage said film.

11. A picture displaying machine comprising a suitable platen having an opening therein, a superimposed sight-tube alining with said opening, a supporting-plate hinged at one side of said platen upon which said tube is mounted, a bracket hinged to and adapted to project from the opposite side of said platen, and adapted to center and guide the lateral movement of the centering ele- 12

ment of a rotatable transparent picture-film, and actuating devices for imparting an intermittent rotary movement and a lateral movement to said film consisting of a reciprocal pitman-beam, and a pick in the rotative reciprocal end thereof adapted to engage said film.

12. A picture displaying machine comprising a suitable platen having an opening therein, a superimposed sight-tube, an artificial light on the side of said platen opposite said tube, means for centering and guiding the lateral movement of the axis of a rotatable film between said tube and platen, and devices for rotating and moving the film laterally.

13. A picture displaying machine comprising a suitably mounted box the top of which constitutes a platen having an opening therein, an artificial light source in said box below said opening, a superimposed sight-tube alining with said opening, means for centering and guiding the lateral movement of the axis of a rotatable transparent film between said tube and opening, a rotatable pick in said box the point of which is adapted to move through a suitably elongated opening in said platen and engage perforations in said film and rotate and move said film laterally.

14. A picture displaying machine comprising a suitably mounted box the top of which constitutes a platen having an opening therein, an artificial light source in said box below said opening, a superimposed sight-tube alining with said opening, a bracket hinged to the side of the box and projecting therefrom for centering and guiding the lateral movement of the axis of a rotatable transparent film between said tube and opening, a rotatable pick in said box the point of which is adapted to move through a suitably elongated opening in said platen and engage perforations in said film and rotate and move said film laterally.

15. A picture displaying machine comprising a suitably mounted box the top of which constitutes a platen having an opening therein, an artificial light in said box below said opening, a superimposed sight-tube alining with said opening, a supporting-plate hinged to one side of said box upon which said sight-tube is mounted, a bracket hinged to the opposite side of said box and projecting therefrom for centering and guiding the lateral movement of the axis of a rotatable transparent film between said tube and opening, a rotatable pick in said box the point of which is adapted to move through a suitably elongated opening in said platen, and engage perforations in said film and rotate and move said film laterally.

16. A picture displaying machine comprising a suitable platen having an opening therein, a superimposed sight-tube alining with said opening, means projecting beyond said platen for centering a film between said tube and platen, and devices for intermittently rotating the film.

17. A picture displaying machine comprising a suitable platen having an opening therein, a superimposed sight-tube alining with said opening, a bracket for centering a film between said tube and platen, and devices for intermittently rotating the film.

18. A picture displaying machine comprising a suitable platen having an opening therein, a superimposed sight-tube alining with said opening, a hinged bracket for centering a film between said tube and platen, and devices for intermittently rotating the film.

In witness whereof I have hereunto set my hand this 18th day of Febr. 1910.

ALEXANDER FERDINAND VICTOR.
